CLAIM

The ornamental design for a container handle, as shown and described.

DESCRIPTION

FIG. 1 is a perspective view of the container handle, from the top, front and left side thereof;

FIG. 2 is a front view thereof;

FIG. 3 is a rear view thereof;

FIG. 4 is a side view thereof (as taken from the left side in FIG. 2);

FIG. 5 is a side view thereof (as taken from the right side in FIG. 2);

FIG. 6 is a top view thereof;

FIG. 7 is a bottom view thereof; and,

FIG. 8 is a perspective view thereof, from a bottom, rear and left side thereof.

The broken lines in the drawings showing the container illustrate environment that form no part of the claimed design.

1 Claim, 8 Drawing Sheets
